OIL SCREEN

Alfred Zech, Detroit, Mich., assignor to Industrial Wire Cloth Products Corporation, Wayne, Mich., a corporation of Michigan

Application February 10, 1940, Serial No. 318,232

5 Claims. (Cl. 210—170)

The present invention relates to floating filters or screens and particularly to devices of this kind specially designed for use in the crankcase of internal combustion engines to screen oil passing to the oil-circulating means.

Among the objects of the invention is a screen of the kind indicated which is provided with a bypass involving no moving parts.

Another object is to further simplify the construction of such devices both in the formation of the parts and in their assembly.

Still another object is a device of the kind indicated which is constructed substantially entirely of sheet metal.

Other objects will readily occur to those skilled in the art upon reference to the following description and the accompanying drawing in which:

Figure 1 is a top plan view of the device with parts in central horizontal section.

Figure 2 is a sectional view on a central vertical plane with parts in elevation and without the outlet tube.

Figure 3 is an end elevation as from the right of Figure 1;

Figure 4 is a section on line 4—4 of Figure 1.

Figure 5 is a section similar to Figure 4 but showing a modified form of construction.

In the drawing, the device is shown as made up of an outer stamped element 10 of which the greater portion forms a bell and has extending from one side a channel 10a, this member being open at its bottom and provided with several ears 10b which are bent over to fix together the assembly.

Inverted in the bell 10 and with the edge soldered, brazed, or otherwise fixed in sealed relation to the inner surface of the bell, is a sheet metal cup 11, serving as a sealed float chamber, and arranged in the space between cup 11 and the outer wall of bell 10 is a cylindrical screen 12, both ends of the screen cylinder being open.

The lower end of the screen 12 and the space between the bell wall and float is covered by a plate 13 provided with a plurality of openings 13a through which oil may pass to the interior of screen 12 in the space between the latter and the float 11. This plate 13 is held in place by bending over the ears 10b.

The channel portion 10a, of bell 10, is preferably closed by a separate plate 14 whose edges are bent over the flanged edge of channel 10a, as shown best in Figure 4.

As indicated in Figures 1, 2 and 4, the oil outlet is through a laterally projecting tube 15 passing through the side walls of channel 10a and riv-

eted over as at 15a to hold it in place. This end of tube 15 is, of course, closed and a lateral opening 15b within the channel 10a permits the out-passage of the oil.

5 The tube 15 may be provided with peripheral ribs or shoulders 15c which allow the filter to be mounted for rotary movement around the axis of the tube without movement longitudinally thereof and this rotary movement is limited by the plate 16 formed with stop lugs 16a.

The plate 16 is preferably provided with an opening for the passage of the tube 15, one of the shoulders 15c serving to hold the plate against channel 10a, and has its lower edge bent over the edge of plate 14, as shown in Figure 4. This structure serves to prevent relative rotation of the plate 16 and channel 10a as well as aiding in maintaining the plate 14 in place.

In order to prevent rotation of the tube 15 in its seats in the walls of channel 10a, the opening in the wall 10c of the channel is preferably provided with notches 15d into which some of the metal of the tube will be pressed during the riveting operation to fix it in place.

25 In Figure 5 is shown a modified form of outlet tube construction which offers some advantages.

In this figure the channel 110a will be of substantially the form of 10a except that, instead of the opening receiving the end of the outlet tube, this far wall of the channel will be provided with a pressed in portion 115a serving as a locator for the end of the outlet tube 115. And the tube 115, instead of being a screw machine part produced from a solid piece, will be a section of tubing.

In producing this structure, the tube 115, stop plate 116, cover 114, and ring 115c and channel 110a will be assembled and the parts brazed together.

As shown clearly in the drawing, the bell 10 and plate 13 may be so formed as to provide seats for the engaging parts, the cup 11, for example, being seated in a suitable groove seat 11a and the screen 12 positioned by suitable shoulders 12a and 12b.

40 45 Further, since in such devices provision must be made for passing oil by the screen in the case of clogging of the latter, the bell 10 is provided with a formed-up portion 20 which permits passage of oil over the screen 12 at 21 from inside the latter to the space between the screen and the bell walls if and when it will not pass through the screen.

Now having described the invention and the preferred embodiment thereof, what is claimed is:

55 1. A floating screen device for screening liquids,

comprising a bell portion having an integral channel portion communicating with the interior thereof, said bell and channel being open, a float chamber within said bell and spaced from the walls thereof, a screen dividing the space between said float chamber and said walls, cover means for closing the said space, said cover means being provided with openings leading to the inside of said screen, cover means for closing the open side of said channel portion, and outlet means for said channel portion.

2. In a floating screen, a sheet metal element constituting a bell with a channel extending therefrom, a substantially cylindrical screen having its upper edge seated in the upper wall of said bell and spaced from the side wall thereof, closure means for said channel, closure means for said bell, the latter means being provided with a seat for the lower edge of said screen and with openings for admitting liquid to the interior of said screen, and means for conducting liquid from said channel outside of said screen.

3. In a floating screen, a sheet metal element constituting a bell with a channel extending therefrom, a substantially cylindrical screen having its upper edge seated in the upper wall of said bell and spaced from the side wall thereof, closure means for said channel, closure means for said bell, the latter means being provided with a seat for the lower edge of said screen and with openings for admitting liquid to the interior of said screen, means constituting a bypass for liquid from within said screen to said channel, said bypass means consisting of a portion of the upper wall of said bell elevated and spaced above 35

the upper edge of said screen whereby to permit liquid to flow over said screen to said channel, and means for conducting liquid from said channel outside of said screen.

4. In a floating screen, a sheet metal element constituting a bell with a channel extending therefrom, a substantially cylindrical screen having its upper edge seated in the upper wall of said bell and spaced from the side wall thereof, a sealed float fixed in said bell within said screen, closure means for said channel, closure means for said bell, the latter means being provided with a seat for the lower edge of said screen and with openings for admitting liquid to the interior of said screen, and means for conducting liquid from said channel outside of said screen.

5. In a floating screen, a sheet metal element constituting a bell with a channel extending therefrom, a substantially cylindrical screen having its upper edge seated in the upper wall of said bell and spaced from the side wall thereof, a sealed float fixed in said bell within said screen, closure means for said channel, closure means for said bell, the latter means being provided with a seat for the lower edge of said screen and with openings for admitting liquid to the interior of said screen, means constituting a bypass for liquid from within said screen to said channel, said bypass means consisting of a portion of the upper wall of said bell elevated and spaced above the upper edge of said screen whereby to permit liquid to flow over said screen to said channel, and means for conducting liquid from said channel outside of said screen.

ALFRED ZECH.
